[57]

ABSTRACT

An improvement in the process for preparing polymers from vinyl chloride monomer in aqueous suspension particularly when using polymerization reaction temperatures of at least about 80°C, comprising the use of hydroxyethylmethylcellulose having a hydroxyethyl MS of about 0.7-3.5 and a methoxyl DS of about 0.6-1.6, as the protective colloid in the water phase of an oil-in-water suspension system.
